(57) **CLAIM**

The ornamental design for a pendant, as shown and described.

DESCRIPTION

FIG. 1 is a perspective view of a pendant.

FIG. 2 is a front view of the pendant of FIG. 1.

FIG. 3 is a right side view of the pendant of FIG. 1, the left side view being a mirror image of the right side view.

FIG. 4 is a rear view of the pendant of FIG. 1.

FIG. 5 is a top view of the pendant of FIG. 1.

FIG. 6 is a bottom view of the pendant of FIG. 1; and,

FIG. 7 is another perspective view of the pendant of FIG. 1. The broken lines shown in the drawings represent portions of the pendant which form no part of the claimed design.

1 Claim, 6 Drawing Sheets
